(No Model.)

L. C. HYDE.

RAILWAY PASSENGER CAR.

No. 367,811.

Patented Aug. 9, 1887.

UNITED STATES PATENT OFFICE.

LOUIS C. HYDE, OF BRIGHTWOOD, MASSACHUSETTS.

RAILWAY PASSENGER-CAR.

SPECIFICATION forming part of Letters Patent No. 367,811, dated August 9, 1887.

Application filed December 23, 1886. Serial No. 222,399. (No model.)

To all whom it may concern:

Be it known that I, LOUIS C. HYDE, of Brightwood, in the county of Hampden and State of Massachusetts, have invented new and useful Improvements in Railway Passenger-Cars; and I do hereby declare that the following is a full, clear, and exact description thereof, reference being had to the accompanying drawings, which form a part of this specification.

This invention relates to certain new and useful improvements in railway passenger-cars, especially that class that is provided with "oval" or "turtle-back" roofs.

In cars of this class an unpleasant feature lies in the fact that no provision is made for lighting the top of the car in the daytime, and also in the absence of means of proper ventilation. As cars are now constructed the only "day" lighting is obtained from the windows situated in the sides of the cars and at a plane considerably below the roof and "bundle-racks," thus rendering to give the top of the car a gloomy appearance, and necessarily bringing the bundle-racks within a deep shadow.

It is the object of this invention to obviate these unpleasant features; and to that end the invention consists in locating windows of the "eyelid" or other suitable ornamental style along the roof at any desired distance apart, all as more fully hereinafter set forth.

Figure 1 is a side elevation of a portion of a passenger-car, two styles of windows being shown in the roof. Fig. 2 is a vertical cross-section on line *xx*, Fig. 1.

In the accompanying drawings, which form a part of this specification, A represents a passenger-car provided with a turtle-back or oval roof; B, the side of the car, which is provided with the usual side windows and panels.

C is the roof-plate upon which the roof is supported at the sides.

The construction of a car thus far described forms no part of my invention whatever, and this construction may be varied to conform to different styles of architecture and ornamental finish, so long as the oval style of roof is incorporated, in contradistinction to the so-called "double-decker."

D are windows, of any suitable and orna-

mental style, formed in the sides of the roof above the roof-plate C, and these windows preferably should be provided with a sash arranged to open in order to assist ventilation. 55

The face of the windows should preferably be upon a vertical parallel plane with the sides of the car, while their position in such vertical plane may be coincident with, inside of, or projecting beyond the side of the car, thereby 60 enabling me to have a greater latitude for change in architectural ornamentation.

It must naturally follow that where windows are inserted in a roof of the character described there must be a connection between the two, 65 so as to exclude the elements, the nature of such connection depending largely upon the relation between the two architectural constructions, and, as this merely calls for the application of ordinary mechanical skill, it 70 forms no part of my invention.

E is a bundle-rack, any desired number of which may be arranged along the top of the car, at the sides, as usual.

A car provided with "roof-windows," substantially as described, will be found light at the ceiling and can be readily ventilated, while it affords a greater scope for aesthetic ornamentation than in cars not so constructed. 75

What I claim as my invention is— 80

1. In a passenger-car having an oval or turtle-back roof, windows placed in said roof above the roof-plate and adjoining the same, substantially as described.

2. In a passenger-car having an oval or 85 turtle-back roof, windows placed in said roof upon either side of the car, the faces of said windows being upon a plane substantially in line with and parallel to the side of the car, substantially as described.

3. In combination with a car, A, provided with an oval or turtle-back roof, B, windows D, let into said roof upon either side of the car, the faces of such windows being upon a plane substantially in line with and parallel 90 with the sides of the car, substantially as specified.

LOUIS C. HYDE.
